UNITED STATES PATENT OFFICE

2,596,738

FURNACE SHELL CONSTRUCTION

Roscoe R. Thomas, Fairfield, Ala., assignor to
 United States Steel Company, a corporation of
 New Jersey

Application May 10, 1949, Serial No. 92,363

4 Claims. (Cl. 266—27)

1

This invention relates to improvements in furnace shell constructions.

Blast furnaces and the like commonly have a refractory lining, an outer steel shell which surrounds the lining, and a layer of insulating material between the shell and the lining. The upper portion of the shell supports the charging mechanism and consequently the shell must remain in alignment to prevent misalignment of the charging mechanism. The upper region of the lining is subject to wear from abrasion of materials charged into the furnace and from the erosive effect of gases. When the lining in this region wears through, the insulating material falls away. The steel shell can withstand temperatures encountered at the top of the furnace, but it tends to warp and thus to lose its alignment.

An object of the present invention is to provide furnaces which embody improved shell constructions for preventing warping of the outer shell in its upper region when the lining wears through.

A further object of the invention is to provide improved furnace shell constructions which embody an inner or auxiliary shell within the outer shell separated therefrom by insulating material, the auxiliary shell and the insulating material thus protecting the main shell against temperatures which cause it to warp.

In accomplishing these and other objects of the invention, I have provided improved details of structure, a preferred form of which is shown in the accompanying drawing, in which:

Figure 1 is a vertical sectional view of a furnace which has an improved shell construction embodying features of the present invention;

Figure 2 is a horizontal sectional view taken substantially on line II—II of Figure 1; and

Figures 3 and 4 are enlarged vertical and horizontal sectional views respectively illustrating the details of the improved shell construction.

In the drawing there is shown the upper portion of a furnace, such as a metallurgical blast furnace. The furnace comprises a refractory lining 10, an outer shell 12 and a charging mechanism 13, all of which can be of any suitable or desirable construction. Also as known in the art, the space between the lining and the shell contains insulating material 14, such as expanded vermiculite, granular diatomaceous earth, ground refractory or earth loam, or, preformed type insulation, such as magnesia blocks.

In accordance with the present invention, outer shell 12 carries an auxiliary shell 16 in its upper region and in spaced relation therefrom. The preferred supporting means for the auxiliary shell

2

comprises a series of sockets 18 fixed to the interior of the outer shell and a series of lugs 17 fixed to the adjacent face of the auxiliary shell and received in said sockets. The auxiliary shell extends around the full circumference of the furnace and is formed of a series of separate steel plates. These plates are spaced arcuately from one another, as shown in Figure 4, to allow for contraction and expansion. Closure strips 18 cover the spaces between the lining plates. These strips are welded to one of the plates adjacent each space and slidably contact the other plate. The lower end of the auxiliary shell preferably has an integral flange 19 which extends toward and preferably abuts the interior of the outer shell. The space between the two shells contains insulating material 14a, which is similar to insulating material 14 already described.

During operation of the furnace, lining 10 wears and eventually wears through. Insulating material 14 falls away as soon as the lining is gone. At this stage the auxiliary shell, rather than the outer shell, becomes exposed to the temperatures prevalent in the upper regions of the furnace, which in iron ore blast furnaces are approximately 500° to 700° F. The steel shell can withstand such temperatures without failing, but it is likely to warp. Such warping is confined to the auxiliary shell, since the layer of insulating material 14a maintains the outer shell at a sufficiently low temperature not to cause warping. Flange 19 on the auxiliary shell prevents loss of insulating material 14a if the lining wears to this depth.

From the foregoing description it is seen that I have provided a simple construction and one which effectively prevents warping of the outer shell of furnaces. The construction can be embodied readily in existing furnaces and overcomes the need for more elaborate means for this purpose, such as water sprays.

While I have shown and described only a single embodiment of the invention, it is apparent that modifications may arise. Therefore, I do not wish to be limited to the disclosure set forth but only by the scope of the appended claims.

I claim:

1. In a furnace having a refractory lining, a metal outer shell surrounding said lining, and insulating material between said shell and said lining, an improved construction for preventing warping of the outer shell in its upper region when said lining wears through comprising an auxiliary shell formed of a series of arcuately spaced metal plates supported on the interior of

said outer shell in its upper region and spaced therefrom, closure strips covering the spaces between adjacent plates and being fixed to one plate adjacent each space and slidably contacting the other, and insulating material between said auxiliary shell and said outer shell.

2. In a furnace having a refractory lining, a metal outer shell surrounding said lining, and insulating material between said shell and said lining, an improved construction for preventing warping of the outer shell in its upper region when said lining wears through comprising an auxiliary shell formed of a series of arcuately spaced metal plates supported on the interior of said outer shell in its upper region and spaced therefrom, flanges on the lower edges of said plates extending toward said outer shell, closure strips covering the spaces between adjacent plates and being fixed to one plate adjacent each space and slidably contacting the other, and insulating material between said auxiliary shell and said outer shell.

3. The combination with a blast furnace which includes an outer shell, a refractory lining spaced inside said outer shell, and charging mechanism at the top of the furnace carried by said outer shell of a device for preventing warping of said outer shell in its upper region when said lining wears through comprising an auxiliary shell car-

ried by the interior face of said outer shell in its upper region and being spaced inwardly of said outer shell and outwardly of said lining, said furnace including insulating material in the space between said lining and said shells next to said lining and additional insulating material in the space between the two shells.

4. A combination as defined in claim 3 in which the lower edge of said auxiliary shell carries a flange extending toward said outer shell for retaining said additional insulating material.

ROSCOE R. THOMAS.
